MOUNTING LIGHT FILTER

Application filed February 23, 1932. Serial No. 594,456.

Our invention relates to illuminating devices and in particular to convenient means for supporting light filters in relation to the source of light. While our invention, as illustrated in the drawing, is shown particularly applied to such use, it is obvious that it may be useful in other arts to connect separated members.

The main objects of our invention are to provide a convenient means for mounting a light filter near a light source and to provide a mounting that is easily detachable so that ready access may be had to the adjacent parts for cleaning, replacement or other purposes. These same objects, and others too numerous to mention, are in view where our invention is used to join any separate elements in other arts, and its use for such purposes, will be obvious. The particular means by which we accomplish these objects will now be fully described.

Referring more particularly to the drawing:

Fig. 1 is a perspective view of our invention applied to a portable lamp of conventional style. The reflector is positioned so as to expose the invention.

Fig. 2 is a top plan view of our invention, part of the lamp reflector being broken away.

Fig. 3 is a sectional view on line 3—3 of Fig. 2, looking in the direction of the arrows.

Fig. 4 is an end elevation of our invention, looking at it from the right of Fig. 2.

Fig. 5 is a section, looking in the direction of the arrows, on line 5—5 of Fig. 6, the reflector being shown in place.

Fig. 6 is a plan view of a portion of a modified form of the invention, the reflector not being shown.

Fig. 7 is a section on line 7—7 of Fig. 8, looking in the direction of the arrows, the reflector being shown in place.

Fig. 8 is a plan view of a portion of another modified form of the invention, the reflector not being shown.

Fig. 9 is a sectional view similar to Fig. 3, showing a modification. Similar numerals indicate similar parts throughout the views.

In Fig. 1, our invention, designated collectively by D, is shown attached to the re-

flector A of a portable lamp having a reflector supporting bracket B, and a standard C. D carries light filter 21, of a color designed to screen out all unwanted radiations from the light source E, which is shown as an incandescent lamp.

The reflector A is formed at its rear lower edge with a step (Fig. 3) comprising a portion 22 bent rearwardly and portion 23 bent downwardly or at some other angle to the portion 22. Almost any arrangement of angularly related surfaces would answer the desired purpose, provided they are not so formed as to allow the clamp to be slid off laterally. This point will be further explained in what follows.

Instead of the single step mentioned, a series of such steps could be used, resulting in a corrugated surface. These steps need not necessarily be parallel but could be arranged in various patterns.

A bowed clamp member 24 is provided with a portion 25 shaped to conform to the convex surface of the step 22 of the reflector and with an opposed portion 26, through which pass the screws 27, in threaded engagement therewith. The screws 27 are directed to fit into the concave surface of the step 22 of reflector A.

The result of this construction is a clamp that cannot be removed by sliding same laterally out of place. It is necessary first to loosen the screws 27.

It has been mentioned above that the surfaces of the reflector step 22 are subject to certain limitations. For instance, if the step consisted of a single plane angularly disposed to the main body of the reflector or if it were a portion of a cylinder and the thickness of the reflector walls were uniform, it would be possible to slide the clamp laterally and remove it without touching the screws 27. So also, with certain forms of steps where the thickness of the reflector walls decreases toward the edge.

To provide greater rigidity the clamp member 24 may also be provided with a lip or extension 28. Where a plurality of steps is used the lip 28 would be formed to conform

thereto and additional holding power secured thereby.

While we have illustrated the screw 27 inside the reflector, a construction in which 5 the relative positions of screws 27 and clamp portion 25 is reversed, is also within our contemplation. In this case the screw heads would be outside of the reflector and the concave surface of steps 22 might be outside instead of inside the reflector.

It is also possible to have the screws 27 press against a convex surface of the reflector step, altho in this case it would be more difficult to secure rigidity. In this case the 15 opposing clamp surface might fit a convex surface on the reflector.

So far it has been tacitly assumed that the reflector walls are substantially uniform in thickness, which is usually the case with 20 blown glassware, or metalware formed from sheets, but it would also be possible to have the reflector walls of variable thickness and to provide one or more ribs and hollows in the reflector. The screws 27 would then, 25 as before, oppose a surface of the clamp member. Care must be taken that the surfaces are so designed as to make it impossible to slide the clamp laterally.

Two screws 27 are illustrated. It would 30 be possible to use only one screw preferably located in the middle of the clamp, or a greater number of screws than two.

The light filter 21 is carried by a pair of 35 channelled brackets 29, fastened to the clamp member 24, either permanently as by welding, soldering or riveting, or removably, as by screws. In the form illustrated the clamp screws 27 pass through the brackets where they are fastened to the clamp member, being 40 also in threaded engagement therewith. This construction provides a longer threaded surface for the clamp screws 27 and makes for greater strength and rigidity.

A retaining means in the form of a leaf 45 spring 30 is provided to hold the light filter frictionally within each bracket 29. This spring is formed with a loop 31 fitting over a tongue 32 formed by slotting the bracket and is put under such tension as to exert pressure 50 against the light filter 21.

Instead of the spring 30 it would also be possible to use a screw or screws 38 (see Fig. 9) passing through one or both the brackets 29. When suitably adjusted these would 55 exert pressure against the light filter 21 and so frictionally hold same against removal from the brackets.

The modification of Figs. 5 and 6 shows 60 a positive retaining means in the form of a screw 33' interposed in each channelled bracket 29'. A modified form of reflector and clamp are shown. The reflector A' has a step 22' formed of angularly related flat surfaces and the clamps 24' are correspondingly formed. There are two clamp members 24'

provided. These are connected by a strip 34' fastened at each end to a clamp member 24', preferably in a permanent manner, such as by welding, riveting or otherwise.

Another modification is shown in Figs. 7 70 and 8. Here the channelled brackets 29'' are extended to form a clamp member 24'', which engages the reflector A''. A clamp screw 27'' is used as before. The two brackets 29'' are connected to each other by strip 34''.

A spring 35'', riveted to channel 29'' at 37'', normally obstructs removal of the light filter 21'' from the channels. On retraction into the position 36'', however, the light filter is removable.

Instead of the screw 33' of Fig. 5, a spring-actuated pin might be used. This might be withdrawn manually when it was desired to slide the light filter either out or in, or its end might be shaped like a blunt wedge, so that when the light filter was slid and sufficient pressure exerted against one of the inclined wedge surfaces, the spring would yield and the pin move out of the way to allow the filter to be inserted or removed.

It will thus be seen that our invention is adapted to carry out all the objects mentioned in a convenient and economical manner.

What we claim is:

1. A reflector having its surface near its edge broken up into one or more steps or ridges, a clamp member having a portion of its surface formed to conform to the steps or ridges on the reflector so as to be complementary or negative thereto, one or more screws mounted in the clamp member in opposed relation to the stepped portion of the clamp member and engaging the inner surface of the reflector so as to draw the complementary surfaces of the clamp member and the reflector together, a pair of grooved brackets carried by the clamp member, a light filter carried by said grooved brackets, and one or more screws carried by the brackets to retain the light filter therein, the relation between the form and arrangement of the steps or ridges of the reflector surface and the co-operative clamp parts being such that when the parts are clamped together the clamp may not be slid laterally along the surface of the reflector.

2. A reflector having a portion of its surface near its edge broken up into one or more steps or ridges, a clamp member having a portion of its surface formed to conform to the steps or ridges on the reflector so as to be complementary or negative thereto, means 125 engaging the inner surface of the reflector adjustably mounted on the clamp member so as to draw the complementary surfaces of the clamp member and the reflector together, grooved brackets carried by the clamp mem-

ber, a light filter carried by said grooved brackets and means carried by the brackets to retain the light filter therein, the relation between the form and arrangement of the 5 steps or ridges of the reflector surface and the co-operating clamp parts being such that when the parts are clamped together the clamp may not be slid laterally along the surface of the reflector.

10 3. A clamp member to connect two elements, one of which is formed with a step comprising two portions, the first portion being in angular relation to the main body of the element, and the second portion angularly related to the first portion, one part of the clamp being formed substantially to the same contour as the step and the adjacent portions of the element, adjustable means carried by the clamp in opposed relation to 15 the first-mentioned part of the clamp and directed toward a concave portion of the stepped portion of said element, and means carried by the clamp for holding the other element.

20 4. In combination, a reflector having its lower edge formed into a step comprising a portion bent outwardly and an adjacent portion bent downwardly, a clamp comprising a channeled portion formed on one side to 25 30 form to the outer surface of the step and the adjacent main portion of the reflector, one or more screws on the opposite side of the channeled portion adapted to engage the inside of the reflector at the junction of the 35 40 outwardly bent and downwardly bent portions of the step, a pair of grooved brackets carried by the clamp, a light filter positioned within the grooved brackets, and retaining means for holding the light filter in place in

5. A combination of elements as defined in claim 4, the retaining means consisting of an element whereby pressure may be applied against the light filter and thereby frictionally oppose its removal from the grooved brackets.

6. A combination of elements as defined in claim 4, the retaining means consisting of one or more screws mounted in the grooved brackets so that their ends press against the light filter and thereby frictionally oppose its removal from the grooved brackets.

7. A combination of elements as defined in claim 4, the retaining means consisting of an element adjustably mounted to open or obstruct the groove of one of the grooved brackets so as to prevent removal of the light filter therefrom when said element is 55 60 in its obstructing position.

8. A combination of elements as defined in claim 4, the retaining means consisting of a movable element mounted so as to normally obstruct the groove of one of the grooved brackets in order to prevent removal of the 65

light filter therefrom but permitting removal when moved from its normal position.

9. A combination of elements as defined in claim 4, the retaining means consisting of an elastic movable element mounted so as to 70 normally obstruct the groove of one of the grooved brackets, thereby preventing removal of the light filter therefrom, but permitting such removal when moved aside from its normal position. 75

Signed at New York, in the county of New York and State of New York this seventeenth day of February, A. D. 1932.

JOSEPH OBERMEYER.
AUGUST BOSTROEM.
